Primary Examiner — Elizabeth A. Albert*(74) Attorney, Agent, or Firm* — Fitzgerald IP Law; John K Fitzgerald, Esq.(57) **CLAIM**

The ornamental design for a bead table, as shown and described.

DESCRIPTION

FIG. 1 is a perspective view of a front, bottom and right side of a bead table showing my new design;

FIG. 2 is a perspective view of the rear, top and left side thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is another front perspective view thereof; and,

FIG. 10 is still another front perspective view thereof.

The broken lines shown are included for the purpose of illustrating portions of the article which form no part of the claimed design.

1 Claim, 10 Drawing Sheets(56)
